CLAIM

We claim the ornamental design for an end gate for a dump truck body, as shown and described.

DESCRIPTION

FIG. 1 is a perspective view of the end gate showing our new design;

FIG. 2 is a rear elevational view of the end gate;

FIG. 3 is a front elevational view of the end gate;

FIG. 4 is a left side elevational view of the end gate, the right side elevational view being a mirror image;

FIG. 5 is a top plan view of the end gate; and,

FIG. 6 is a bottom plan view of the end gate.

The broken lines shown are for illustrative purposes only and form no part of the claimed design.
